UNITED STATES PATENT OFFICE

169,399

EMBORESSED TEXTILE FABRIC OR SIMILAR ARTICLE

Herman Wagner, New York, N. Y.

Application February 26, 1953, Serial No. 23,808

Term of patent 14 years

(Cl. D92—1)

To all whom it may concern:

Be it known that I, Herman Wagner, a citizen of the United States of America, residing in New York, county of New York, and State of New York, have invented a new, original, and ornamental Design for an Embossed Textile Fabric or Similar article, of which the following is a specification, reference being had to the accompanying drawing, forming part thereof.

The figure illustrates a plan view of an embossed textile fabric or similar article, showing my new design.

A design unit is outlined by broken lines and is repeated as indicated. My design is characterized by the diamond pattern produced by the diagonally intersecting loosely tied raised ribbon like elements.

I claim:

The ornamental design for an embossed textile fabric or similar article, substantially as shown and described.

HERMAN WAGNER.
